TOY CANNON

William C. Peterson, 31 Water St., Claremont, N.H.

Filed Dec. 30, 1963, Ser. No. 77,953

Term of patent 7 years

(Cl. D34—15)

FIG. 1

FIG. 2

FIG. 3

I claim:

The ornamental design for a toy cannon, as shown and described.
